UNITED STATES PATENT OFFICE

116,689

DESIGN FOR A COMBINATION SIGNBOARD AND DANGER REFLECTOR

Green Lee Joyce and Ernest L. Oakley,
Bassett, Va.

Application January 24, 1939, Serial No. 82,577

Term of patent 7 years

To all whom it may concern:

Be it known that we, Green Lee Joyce and Ernest L. Oakley, citizens of the United States, residing at Bassett, in the county of Henry and State of Virginia, have invented a new, original, and ornamental Design for a Combination Signboard and Danger Reflector, of which the following is a specification, reference being had to the accompanying drawing, forming a part thereof.

Fig. 1 is a front elevation of a combination

signboard and danger reflector showing our new design.

Fig. 2 is a side elevation of the same.

What we claim is:

The ornamental design for a combination signboard and danger reflector, substantially as shown.

GREEN LEE JOYCE.
ERNEST L. OAKLEY.
